UNITED STATES PATENT OFFICE.

HARLEY S. NELSON, OF COEUR D'ALENE, IDAHO.

ASH-PAN.

1,238,555.

Specification of Letters Patent. Patented Aug. 28, 1917.

Application filed December 5, 1916. Serial No. 135,206.

To all whom it may concern:

Be it known that I, HARLEY S. NELSON, a citizen of the United States, residing at Coeur d'Alene, in the county of Kootenai 5 and State of Idaho, have invented new and useful Improvements in Ash-Pans, of which the following is a specification.

This invention relates to ash pans adapted to be used in stoves or ranges for the purpose of catching and collecting the ashes as they fall from the grate and it consists in 10 the novel features hereinafter described and claimed.

An object of the invention is to provide an 15 ash pan of the character stated which is of simple and durable structure and which may be placed in the ash pit of a stove or range for the purpose of catching the ashes. The said pan is provided at the upper edges of 20 its sides with hinged panels and at its rear end with a hinged panel and pivoted side flanges adapted to be connected with the last mentioned panel whereby all of the said 25 panels may be swung to an open position simultaneously. A rod is operatively connected with the rear end panel and may be used for swinging the same and through the connection between the flanges and the top panels the said top panels are also closed 30 as the rear panel is closed. A catch device is provided upon the rear panel and is adapted to engage keepers upon the flanges temporarily fixed with relation to each other.

35 In the accompanying drawing:

Figure 1 is a perspective view of the ash pan;

Fig. 2 is a longitudinal sectional view of the same.

40 Fig. 3 is a transverse sectional view cut on the line 3-3 of Fig. 2.

Fig. 4 is a detailed horizontal sectional view of a portion of the pan cut on the line 4-4 of Fig. 1.

45 The ash pan is made from sheet metal and comprises a bottom 1, side walls 2 and an end wall 3. A bracing strip 4 extends transversely across the end wall 3 and the said pan may be otherwise suitably braced 50 if desired. Cover panels 5 are hingedly connected at the upper edges of the side walls 2 and an end panel 6 is hingedly mounted at the rear edge of the bottom 1. The said end panel 6 is provided at its ends with 55 turn bends 7 which are adapted to lie in close proximity with the rear edges of flanges

hereinafter described when the end panel 6 is in a closed position and thus prevent the escape of the ashes between the edges of the flanges and the said panel 6. The panel 6 60 is mounted upon a shaft 10 which is journaled in the sides of the pan and the said shaft is provided with a crank 11. The flanges 8 are pivoted on the shaft 10 at the edges of the panel 6. The free ends of the 65 flanges 8 lie under the cover panels 5 and are connected therewith by means of chain sections 9. A rod 12 is pivotally connected at one end with an annularly disposed end of the rod 10 and passes transversely through 70 a projecting end portion of the strip 4 as best shown in Fig. 1. The forward end of the rod 12 is fashioned in the form of a handle 13. Keepers 14 are mounted at the 75 upper portions of the rear edges of the flanges 8 and a gravity actuated catch 15 is movably mounted upon the panel 6 and its end portions are adapted to be engaged in the keepers 14 whereby the flanges 8 may be 80 fixed with relation to the panel and swing with the same.

In operation, the catch 15 is engaged in the keepers 14 and the pan is inserted in the ash pit of the stove or range. The rod 12 85 is moved rearwardly whereby the panel 6 is swung to an inclined position with relation to the body of the pan. During such swinging movement of the panel 6 the free ends of flanges 8 strike the under surfaces of the cover panels 5 and swing them to 90 open inclined position above the upper edges of the side walls 2 of the pan. Thus the said panels are in position to direct the ashes which may fall upon them into the body of the pan. When it is desired to remove the pan from the ash pit the rod 12 95 is moved in a forward direction whereby the panel 6 is moved to a vertical or closed position. During the last mentioned swinging movement of the end panel 6 the chains 9 100 are moved longitudinally whereby the cover panels 5 are swung from open to closed positions and thus the pan is completely closed. The pan is then removed from the ash pit and its end placed over the upper edge of the 105 ash receptacle. The catch 15 is then lifted out of the engagement with the keepers 14 and the panel 6 is swung rearwardly and hence the contents of the pan are permitted to slide from the same into the ash receptacle. 110

Thus it will be seen that the ashes may

be removed from the pit without permitting the dust therefrom to fly in the neighborhood and also the ashes may be shifted from the pan to a receptacle in a manner to minimize the escape of dust.

From the foregoing description taken in conjunction with the accompanying drawing, it will be seen that an ash pan of simple and durable structure is provided and that 10 the same may be easily and quickly manipulated to facilitate the removal of ashes from a pit of a stove or range and also for depositing them in a receptacle without permitting the dust to escape from the ashes 15 during the removal of the same.

Having described the invention what is claimed is:—

An ash pan comprising a body having a

Copies of this patent may be obtained for five cents each, by addressing the "Commissioner of Patents, Washington, D. C."

bottom, side walls and an end wall, panels hinged upon the side walls, a panel hingedly 20 mounted between the side walls, a rod operatively connected with the last mentioned panel for swinging the same, flanges pivoted on the rod at the edges of the second mentioned panel and being movable with relation to said panel, and having free end portions lying under the first mentioned panels, flexible elements connecting said flanges with the first mentioned panels, keepers mounted upon the flanges, and a 25 gravity catch mounted on the second mentioned panel and adapted to engage and disengage the keepers.

In testimony whereof I affix my signature.

HARLEY S. NELSON.
